INVENTOR
THOMAS Y. STEWART.
BY Paul & Paul
HIS ATTORNEYS.

UNITED STATES PATENT OFFICE.

THOMAS YOUNG STEWART, OF ST. PAUL, MINNESOTA, ASSIGNOR, BY DIRECT AND MESNE ASSIGNMENTS, OF FIVE-SIXTHS TO SAID THOMAS Y. STEWART AND RONALD STEWART.

FEED-WATER HEATER.

No. 852,466.

Specification of Letters Patent.

Patented May 7, 1907.

Application filed December 27, 1904. Serial No. 238,285.

To all whom it may concern:

Be it known that I, THOMAS YOUNG STEWART, of St. Paul, Ramsey county, Minnesota, have invented certain new and useful Improvements in Feed-Water Heaters and Purifiers, of which the following is a specification.

This invention relates to improvements in devices designed for heating and purifying water that is to be fed to a steam boiler, and the object that I have in view is to provide a device of this character that will be simple and inexpensive in construction, effective in operation, and take up but a small amount of space so that it may be used upon locomotives, as well as in connection with stationary boilers.

The invention consists generally in the constructions and combinations hereinafter described and particularly pointed out in the claims.

In the accompanying drawings, forming part of this specification, Figure 1 is a longitudinal sectional view of a feed water heater and purifier embodying my invention. Fig. 2 is a transverse vertical section on line 2—2 of Fig. 1. Fig. 3 is a partial vertical section on line 3—3 of Fig. 1. Fig. 4 is a partial horizontal section on line 4—4 of Fig. 1.

In the drawing, 2 represents the main separating chamber consisting preferably of a piece of cylindrical pipe of any suitable length. One end of this pipe is secured to cylinder 3 by means of a flanged plate 5. The opposite end of the chamber 2 is connected to a tube sheet 6 and a header 7 by means of a flanged plate 8 and suitable bolts 9. Arranged within the cylinder 3 is a tube sheet 10 and the header 11 secured to the wall of the cylinder by suitable means, such as a bolt 12. The header 11 is secured to the tube sheet 10 by the bolts or screws 13, and said header and tube sheet rest upon a bracket 14 secured to the inner wall of the cylinder. A series of copper tubes 15 pass through the chamber 2 having their ends passing through the tube sheets 6 and 10. The forward ends of the tubes are secured in a plate 16 that is secured to the tube sheet 6 by suitable screws or bolts 17. Suitable packing may be provided around each tube between the plates 6 and 16 (see Fig. 1.) A steam inlet pipe 18 is connected to the header 7, and a water inlet pipe 19 is connected to the chamber 2.

A series of transverse plates 20, preferably formed of zinc, are arranged within the chamber 2 and surrounding the tubes 15, each of said plates being provided with a series of openings through which said tubes pass. The plates 20 are cut away alternately at top and bottom so as to form a zig-zag water passage through said chamber, thereby causing the water that enters the chamber through the pipe 19 to pass back and forth from one side of the chamber to the other around the tubes 15, as indicated by the arrows in Fig. 1. The cylinder 3 is preferably provided with a top 21 and a bottom 22 and the part of the cylinder below the tubes 15 forms a settling chamber. A series of perforated circular zinc plates 23 are preferably arranged in this chamber. The bottom of the chamber is also preferably provided with a suitable waste pipe 24 which may be provided with a suitable valve.

The upper part of the cylinder 3 is provided with a horizontal partition 25, and a second horizontal partition 26 preferably at a lower level than the partition 25. An upright perforated wall 27 connects the partitions 25 and 26. Above the partition 25 is a chamber 28 provided with a series of baffle plates 29 perforated near their upper and lower edges, and connected to this chamber is the water outlet pipe 30. A pipe 31 is preferably connected to the space between the header 12 and the tube sheet 10 and extends lengthwise of the chamber 2 near the bottom thereof and through the tube sheet 6, the plate 16 and the header 7. This pipe carries off the water of condensation from the header 11.

Operation: The operation of the device is as follows: The water is fed by suitable means, such as an injector, through the pipe 19 into the separating chamber 2. It passes along in said chamber between the plates 20, by which it is compelled to pass back and forth from one side of the chamber to the other and between and around the copper tubes 15. As the water passes back and forth from one side of the chamber to the other it is agitated and heated. As the plates are made of zinc and the tubes of copper a galvanic action is thereby obtained which, while it is insufficient to decompose the water, gives sufficient directive force to

cause any oxygen in the water to go to the zinc plates and corrode them instead of corroding the boiler. It is for this purpose that I provide the zinc plates 23 in the bottom 5 of the settling chamber. These plates are easily removable and their use in the settling chamber reduces the corrosion of the boiler.

I claim as my invention:

1. In a feed water heater and purifier, the combination, with a separating chamber provided at its ends with suitable tube sheets and headers secured to said tube sheets, of a series of transverse zinc plates arranged in said chamber, alternate plates being provided with spaces between their edges and the wall of the chamber, and a series of copper tubes extending through said chamber and through openings in said plates, substantially as described.
2. In a feed water heater and purifier, the combination, with a separating chamber provided at its ends with suitable tube sheets, and headers inclosing said tube sheets, of a series of copper tubes extending through said chamber and having their ends arranged in said tube sheets, and a series of transverse zinc plates arranged in said chamber and provided with openings for the passage of said tubes, spaces being provided between 25 the edges of alternate plates and the walls of the chamber, for the purpose set forth.
3. In a feed water heater and purifier, the combination, with a separating chamber, of a series of copper tubes extending through said chamber, a series of transverse zinc plates

extending across said chamber and surrounding said tubes with spaces arranged at the edges of alternate plates, means for passing water through said chamber, and means for passing steam through said tubes, substantially as described. 40

4. The combination, with the cylinder 3, of the separating chamber 2 connected therewith, the series of copper tubes 15 arranged in said chamber, the series of transverse zinc 45 plates 20 also arranged in said chamber, the series of zinc plates 23 arranged in said cylinder below said tubes, and suitable baffle plates arranged in the upper part of said cylinder. 50

5. In a feed water heater and purifier, the combination, with a separating-chamber provided at its ends with suitable headers, of a series of tubes extending through said chamber, one or more tube sheets supporting said 55 tubes, a series of transverse plates arranged in said chamber and provided with openings for the passage of said tubes, with spaces between the edges of alternate plates and the walls of the chamber, said plates being arranged in series throughout the body of said chamber, and a settling chamber arranged below said separating-chamber and provided with a series of zinc plates. 60

In witness whereof, I have hereunto set my hand this 14th day of December 1904.

THOMAS YOUNG STEWART.
